Primary Examiner — Garth Rademaker*Assistant Examiner* — Aaron C Fowler(74) *Attorney, Agent, or Firm* — Condo Roccia Koptiw LLP**CLAIM**

The ornamental design for a snorkel head assembly as shown and described.

DESCRIPTION

FIG. 1 is a perspective view of the snorkel head assembly according to the present application;

FIG. 2 is a front view of FIG. 1;

FIG. 3 is a rear view of FIG. 1;

FIG. 4 is a top view of FIG. 1;

FIG. 5 is a bottom view of FIG. 1;

FIG. 6 is a side view of FIG. 1;

FIG. 7 is a side view of FIG. 1; and,

FIG. 8 is the perspective view of FIG. 1 with an inlet screen (in broken line) attached to the snorkel head assembly. The dot-dot broken lines are included for the purpose of illustrating portions of the article that form no part of the claimed design. The dash-dot broken lines are included for the purpose of illustrating a boundary of the claim and form no part of the claimed design.

The shade line showing is included for the purpose of illustrating contour and not surface ornamentation.

1 Claim, 8 Drawing Sheets(56)
